UNITED STATES PATENT OFFICE.

FRANK H. FERAUD, OF GRANITE CITY, ILLINOIS.

MOTOR.

1,185,648.

Specification of Letters Patent.

Patented June 6, 1916.

Application filed October 26, 1914. Serial No. 868,627.

To all whom it may concern:

Be it known that I, FRANK H. FERAUD, a citizen of the United States, residing at Granite City, Illinois, have invented a certain new and useful Improvement in Motors, of which the following is a full, clear, and exact description, such as will enable others skilled in the art to which it appertains to make and use the same.

- 10 This invention relates to motors, and more particularly to that class of motors that are employed for winding clocks, or for operating other light machinery, such as window-display novelties, etc.
- 15 One object of my invention is to provide a motor of the class described that can be successfully operated on a comparatively high voltage current, either alternating or direct, such as is supplied to consumers in 20 cities by public service companies.

Other objects are to provide a motor of the class described that is light in weight, efficient and economical in operation, that is not liable to get out of order, and which 25 comprises few simple parts that can be produced at a low cost of manufacture.

Further objects and desirable features of my invention will be hereinafter pointed out.

- 30 Figure 1 of the drawings is a side elevational view with part of the frame-work removed, illustrating a motor constructed in accordance with my invention and operatively connected to a clock train. Fig. 2 is a front elevational view thereof. Fig. 3 is a vertical sectional view taken approximately on the line 3—3 of Fig. 2, parts being broken away, so as to more clearly illustrate the invention. Fig. 4 is a view similar to 35 Fig. 3, showing the moving parts of the motor in a different position. Fig. 5 is a transverse sectional view taken approximately on the line 5—5 of Fig. 2. Fig. 6 is a detail perspective view, illustrating 40 the primary actuating member of the motor and its carried parts. Fig. 6^a is a detail sectional view taken approximately on the line a—b of Fig. 3. Fig. 7 is a side elevational view, illustrating a slightly modified 45 form of my invention. Figs. 8 and 9 are detail elevational views, illustrating different forms of the primary actuating member. Fig. 10 is a diagrammatic view, 50 illustrating the various electric elements 55 and their connections.

Briefly described, my invention consists

in a motor that is provided with a rotatable driving element that is adapted to be suitably connected to the work that is desired to be operated, a primary actuating member 60 for actuating said element, means for moving said primary actuating member in one direction in order to actuate said driving element, and electrical means for moving said member in the opposite direction so as 65 to store up energy therein.

Referring to Figs. 1 to 6 of the drawings which illustrate the preferred form of my invention, A designates the frame of the motor in which is journaled the main shaft B. 70 The driving element that is adapted to be connected to the work that is desired to be operated consists of a pinion C having conjoined therewith a ratchet wheel D, said element being loosely mounted on the shaft B. 75 The means for actuating the pinion C consists of an arm E, which I will term the primary actuating member of the motor, said arm being journaled on the shaft B adjacent the ratchet wheel D, and having arranged 80 thereon a pawl 1 that engages the teeth on the periphery of said wheel. The pawl 1 preferably consists of a thin strip of flexible material, such as spring metal that is securely clamped in position on the arm E at 85 the outer end thereof by any suitable means, such as lugs e' that are bent over a projecting portion of said pawl. The pawl 1 is provided at its inner or free end with an enlarged portion 1^a that engages the teeth of 90 the ratchet wheel D, a part of said portion 1^a lying in a notch e² formed in an extension e³ of the arm E. As shown in Figs. 6 and 6^a, a shoulder formed at the junction of the portion 1^a and the body portion of the pawl 95 1 engages the bottom of the notch e², and thus prevents said pawl from being distorted or from being forced backwardly out of engagement with the ratchet wheel D, if, for any reason, said ratchet wheel is given a 100 retrograde movement.

The primary actuating member E is adapted to oscillate about the shaft B as an axis, movement in one direction causing the pinion C to rotate through the medium of 105 the pawl and ratchet mechanism heretofore described, and movement in the opposite direction causing the pawl to ride freely over the teeth on the ratchet wheel D. Means is provided for causing said primary actuating 110 member to move in a direction to rotate the pinion C, the means herein shown consisting

of a comparatively heavy coiled expansion spring F, having one end connected to said member, and its opposite end securely anchored to some stationary part of the frame 5 A. I wish it to be understood, however, that my invention is not limited to use with a spring of the exact type shown, as various other types of springs could be successfully utilized to actuate the arm E on its power 10 stroke. In order to move the primary actuating member in a direction to store up energy in the spring F attached thereto, I provide said member with a plunger 2 that is yieldingly connected thereto in the manner to be hereinafter described, and which is adapted to be pulled upwardly by means of an electro-magnetic coil or solenoid G that is suitably connected, as by means of brackets g to the frame A. The solenoid 15 G is energized by a suitable source of electrical energy 4, which may be either alternating or direct current of a comparatively high voltage, and means is provided for demagnetizing said solenoid for certain periods of time during the cycle of operations 20 of the motor.

When the motor is idle the parts are in the position shown in Fig. 1, and when it is desired to operate said motor, the solenoid 25 G is energized by closing the circuit 4 and the magnetic force therein pulls the plunger 2 upwardly and stores up energy in the spring F. When the spring is "wound up" or energized, means is provided for automatically breaking the electric circuit of the solenoid G, so as to demagnetize same and allow the primary actuating member E to move downwardly on its power stroke to the position shown in Fig. 1, under the influence of the spring F, and thus impart 30 rotary movement to the pinion C. As soon as the actuating member E reaches the position shown in Fig. 1, that is, the end of its power stroke, means is provided for automatically energizing the solenoid G, so that 35 it will again pull the plunger upwardly, and thus repeat the cycle of operations just described. It will thus be seen that the primary actuating member E is alternately 40 moved in one direction about its axis by means of the solenoid G, and in the opposite direction by means of the spring F, this latter movement, through the medium of the pawl 1 and ratchet wheel D, imparting 45 an intermittent rotary movement to the pinion C. The means for alternately making and breaking the circuit that is connected to the solenoid G, as herein shown, preferably consists of a member 5 provided 50 with an outwardly extending projection to which the plunger 2 is connected by means of a link 3, and said member is pivotally connected at 6 to the primary actuating member E and provided with a brush or shoe 7 that coöperates with a device 8 that

is arranged concentrically with respect to the axis of the arm E. The brush 7 is loosely mounted on a pin 9 that is secured in a block of insulating material 10 that is fastened to the member 5, and a flat leaf 70 spring 7^a bears against said brush so as to always tend to force the same inwardly. The device 8 comprises two metallic contacts or segments 8^a that are spaced apart, and connected in the circuit that energizes 75 the solenoid G. When the motor is idle, or in the position shown in Fig. 1, the brush 7 bridges the gap or space between the segments 8^a, so that when the current is turned on the circuit is completed by passing from one segment to the other through the brush 7, and the solenoid G will be energized, and pull upwardly on the plunger 2, the movement of the plunger upwardly causing the primary actuating member E and the 80 member 5 carried thereby to move about the shaft B, so as to store up energy in the spring F.

The plunger 2 being connected to the member 5 at a point outwardly removed from the point at which said member is pivotally connected to the arm E, will, on its upward stroke, move the member 5 about the axis of rotation of the arm E and at the same time exert inward pressure on the 85 brush 7, so as to keep the same in intimate engagement with the contact segments 8^a. As soon as the plunger is moved upwardly far enough to carry the brush 7 past the space between the segments 8^a, the circuit 100 will be automatically broken and the primary actuating member will be returned to its lowermost position on its power stroke under the influence of the spring F. As soon as the arm E starts to move downwardly, the member 5 swings outwardly away from the segments 8^a, owing to gravity, or the pressure of the flat leaf spring 11 that bears against a projection 12 on said member, said projection 12 being 105 arranged in a slot 12^a formed in the arm E, so as to restrict the movement of the member 5 about its pivot point 6. Outward movement of the member 5 carries the brush 7 away from the segments 8^a, as shown clearly in Fig. 4, and said brush is held out of contact therewith until the arm E has reached its lowermost position, as shown in Fig. 3, when a tail or extension 13 on the member 5 engages a stationary post 14 on the frame A, and thus causes said member to move about its pivot point against the pressure of the spring 11, so as to again engage the brush 7 with its coöperating segments 8^a, when the circuit is again closed 110 to energize the solenoid G. The solenoid exerts a sudden upward pull on the plunger 2 and holds said brush in engagement with said segments until the circuit is broken by reason of the brush crossing the gap be- 115

tween said segments. In order to limit the upward movement of said plunger and also to dampen the shock of the sudden stopping thereof, I provide a cushioning device or 5 spring 15 on the member 5 that engages the post 14 when said member approaches the end of its upward stroke.

The electrical connections between the solenoid G and the contact segments 8^a are 10 shown clearly in Fig. 10, wherein it will be seen that the supply conductors 4 are attached to the binding posts 4^a, or, if desired, to a suitable receptacle, from which the positive conductor 4^b leads directly to one of 15 the segments 8^a, and the negative conductor 4^c leads to and through the solenoid G and thence to the other segment. A choke coil H is preferably arranged in the circuit, as shown, for preventing a destructive spark 20 or flash from occurring when the brush 7 passes over the space between the segments 8^a.

In Fig. 1 I have shown the motor as being attached to a clock train for the purpose of 25 automatically winding the main spring 16 thereof, the pinion C being at all times in mesh with the gear wheel 17 that is controlled by said spring. When the motor is employed, as shown in Fig. 1, to operate a 30 piece of mechanism wherein there is practically no momentum present to keep the driving element constantly rotating, it is necessary to provide means for preventing retrograde movement of said element, the means 35 herein shown consisting of a spring-pressed locking pawl 18 that coöperates with the ratchet wheel D, so as to prevent said wheel from being moved backwardly when the primary actuating member is moving on its 40 upward stroke to store up energy in the spring F.

In Fig. 7 I have illustrated a construction 45 wherein the motor can be used for various driving purposes, and in the instance shown, the gear wheel C' is substituted for the pinion C and is in mesh with a pinion 19 that is mounted on a shaft 20, to which is connected a suitable driving pulley 21, or, if desired, said shaft may be provided with 50 a crank arm or other suitably driving means.

While I have hereinbefore referred to the means for moving the primary actuating member on its power stroke as a spring, I 55 wish it to be understood that my invention is not limited to such a construction, as a weight F' attached to the primary actuating member E' (see Fig. 7) could be substituted for the spring F previously described, said weight acting to move the primary actuating member on its power stroke by gravity.

Under certain conditions in service, as 60 when using alternating current to store up energy in the primary actuating member E', it is desirable to provide means for absorbing the "chatter" or vibration that

would otherwise occur in the solenoid G, the means herein shown consisting of a yielding connection between the link 3^a and the plunger 2, said link being provided with a slot that coöperates with the pivot pin 3^b 70 in the plunger 2, and a coiled expansion spring 22 is connected to said link and to said pivot pin, so that the plunger 2 is free to vibrate within certain limits, irrespective of the link 3^a.

In Fig. 8 I have shown a slightly different arrangement of the primary actuating member and its carried parts, the member 5^a that carries the brush 7 being pivoted at 6^a adjacent the outer end of the primary 80 actuating member E², and the plunger 2 is connected to the member 5^a at a point intermediate the pivot point 6^a thereof and the axis of revolution of the member E². In Fig. 9 the member 5^b that carries the brush 85 7 is shown as being pivotally connected to an extension 23 of the primary actuating member E³ in such a manner that an upward pull on said member always tends to force the brush 7 into intimate contact with 90 the segments 8^a.

From the foregoing it will be seen that I have produced a highly efficient motor that is very economical in its consumption of current, owing to the fact that the current is only utilized intermittently, that is, for only one-half of the stroke of the primary actuating member, in order to store up energy therein.

I am aware that many minor changes may 100 be made in the construction and arrangement of the parts constituting my invention without departing from the spirit thereof.

Having thus described my invention, 105 what I claim and desire to secure by Letters Patent is:

1. In a motor, a shaft, a driving element journaled on said shaft, a primary actuating member that is adapted to oscillate 110 about said shaft, means for connecting said member to said element when said member is moving in one direction, a solenoid for moving said member in the opposite direction, a pair of contacts arranged concentrically with respect to said shaft and comprising two spaced metallic segments, a co-operating brush carried by said member, an electric circuit for said solenoid, which, when closed, includes said segments and co-operating brush as conducting parts thereof, and means for causing said brush to leave said segments so as to break said circuit during a certain period in the cycle of operations of the motor.

2. In a motor, a shaft, a driving element journaled on said shaft, a primary actuating member that is adapted to oscillate about said shaft, means for connecting said member to said element when said member 120

is moving in one direction, a solenoid for moving said member in the opposite direction, a device arranged concentrically with respect to said shaft and comprising two spaced metallic segments, a coöperating brush carried by said member, an electric circuit for said solenoid, which, when closed, includes said segments and coöperating brush as conducting parts thereof, means 5 for yieldingly holding said brush in contact with said segments to close the circuit when the member is moving in one direction, and means for holding said brush out of contact with said segments when said member is moving in the opposite direction.

3. In a device of the character described, a shaft, a driving element journaled on said shaft, a primary actuating member mounted on said shaft, said member being adapted 20 to oscillate about said element, means for connecting said member to said element when said member is moving in one direction, a device pivotally mounted on said member, a spring-pressed brush carried by

said device, a coöperating pair of contacts 25 arranged concentrically with respect to said shaft, a slot and pin connection between said device and said member at a point outwardly removed from the pivot point thereof, a solenoid for moving said device 30 in one direction, an electric circuit for energizing said solenoid that includes said contacts and brush, means for automatically breaking the circuit when said device has been moved a certain distance by said solenoid, means for moving said primary actuating member and its carried device in the opposite direction so as to actuate said driving element, and means for holding said circuit open during the actuating stroke of 40 said member.

In testimony whereof I hereunto affix my signature in the presence of two witnesses, this twenty-third day of October, 1914.

FRANK H. FERAUD.
